UNITED STATES PATENT OFFICE.

FRANK L. CROSS, OF MYSTIC, CONNECTICUT, ASSIGNOR TO CROSS PAPER FEEDER COMPANY, OF BOSTON, MASSACHUSETTS, A CORPORATION OF MAINE.

CONTROLLING MECHANISM FOR MACHINES ACTING ON SHEETS.

No. 854,080

Specification of Letters Patent. Patented May 21, 1907.

Application filed April 3, 1905. Renewed November 2, 1906. Serial No. 341,782.

To all whom it may concern:

Be it known that I, FRANK L. CROSS, of Mystic, in the county of New London and State of Connecticut, have invented certain new and useful Improvements in Controlling Mechanism for Machines Acting on Sheets, of which the following is a specification.

The invention relates to mechanism for controlling machines designed to act upon sheets so that the machine may be automatically stopped or thrown out of operation whenever a sheet is not fed into the proper position to be acted upon.

The object of the invention is to provide a controlling mechanism of this character which shall be simple in construction and reliable in operation and which may be readily adapted for use in connection with printing presses to which sheets are automatically fed by sheet feeding mechanism.

In practicing my invention I operate the mechanism which throws the machine out of operation, through an arm connected with said mechanism and having its free end arranged at one side of the path of the sheets. The front end of the arm is provided with a shoulder or recess arranged in the path of movement of an actuator which is located on the opposite side of the path of the sheets. When a sheet is properly fed it lies between the arm and the actuator at the time the actuator is advanced and prevents the engagement of the actuator with the notch or recess in the arm. If, however, the sheet is not properly fed or positioned, the actuator as it moves forward engages the notch or recess in the arm and moves said arm, thus operating the throw-out mechanism and causing the stopping of the machine.

In adapting my invention for use in connection with printing presses, I arrange the arm which is connected with the throw-out mechanism, above the path of the sheets and with the shoulder or recess just back of the front edge of the sheet when the sheet is against the front gages of the printing press. When the sheet is brought into position with the front edge against the front gages, it lies below the shoulder or recess in the arm and in the path of the actuator as it advances toward the shoulder or recess. I prefer to employ as an actuator, a bar arranged to be reciprocated in line with the shoulder or recess

and to engage the under surface of the sheet when said sheet is properly positioned. When the sheet is properly positioned between the actuator bar and the arm connected with the throw-out mechanism, the actuator moves along the under surface of the sheet during its advance movement and the engagement of the actuator with the shoulder or recess in the arm is prevented. In order that the sheet may move to accommodate the movement of the actuator, the arm is pivotally supported to swing upward as the actuator passes along the under surface of the sheet, thereby lifting it. When the sheet is not in proper position the actuator during its advance movement engages the recess or shoulder on the arm and operates the throw-out mechanism. This construction and arrangement enables the parts of the mechanism, the engagement of which is controlled by the presence of the sheet, to be arranged close to the surface of the impression cylinder and at the same time to act efficiently and positively in throwing the machine out of operation whenever a sheet is not properly fed. This construction also avoids any danger of throwing the machine out of operation so long as the sheets are properly positioned between the actuator and the arm through which the actuator is connected with the throw-out mechanism.

The various features of the invention will be understood from the following detailed description of the mechanisms shown in the drawings which embody the various features of the invention in the forms in which I prefer to employ them.

In these drawings Figure 1 is a plan view showing one side of a feed board for a printing press with the controlling mechanism applied thereto. Fig. 2 is a side elevation, certain parts being removed and other parts shown in section for the sake of clearness. Figs. 3 and 4 are enlarged details showing the free end of the arm through which the throw-out mechanism is operated. Fig. 5 is a partial detail showing a modified form of connection between the arm and its support, and Fig. 6 is an enlarged perspective view showing a modified form of connection between the actuator bar and throw-out mechanism arm.

In the construction shown in the drawings,

A indicates the impression cylinder of a printing press to which the sheets are successively presented by being moved or fed into position against the front gages A of the press. The sheets may be fed by any suitable mechanism or by hand and when automatically fed the feeding mechanism should be driven by suitable connections with the mechanism for operating the press, so that both the feeding mechanism and the press may be thrown out of operation simultaneously in case a sheet is not properly presented and registered against the front gages.

15 In the construction shown in the drawings the sheets are fed by any suitable automatic mechanism over the support B which is arranged on the front end of the feed board B'

20 The mechanism for throwing the machine out of operation includes an arm C secured to a hollow rock shaft or sleeve C' and connected by means of a link C² with any suitable form of stop mechanism. The stop mechanism may be of any suitable and well known construction, such for instance as an electric switch or mechanical or electric devices which are either released or operated by the movement of the link C².

25 The sleeve C' is loosely mounted upon a rock shaft D which extends transversely of the machine above the sheet support B. The sleeve C' remains at rest so long as the sheets are properly fed. The sleeve is 30 rocked, however, to operate the arm C and connected parts of the stop mechanism in case a sheet is not properly fed through an arm C³ connected with the sleeve.

35 The arm C³ extends in an inclined direction toward the line of the front gages A and is so arranged that its free end lies above the sheet when the sheet is in position against the front gages. A recess C⁴ is formed in the under side of the arm C³ near its free end and 40 the end of this recess forms a shoulder C⁵ which lies just back of the line of the front gages. This shoulder is also arranged in position to be engaged by the end of an actuator bar E arranged below the path of 45 the sheet and reciprocated in a line intersecting the path of the sheet and passing through the shoulder C⁵.

50 The reciprocation of the actuator bar E is so timed with relation to the feeding mechanism that the bar E is advanced just after the front edge of the sheet engages the front gages when the sheet is properly fed. With the sheet in this position the front end of the bar as it advances, presses against the under 55 surface of the sheet which rises somewhat as the bar advances so that the end of the bar passes idly by the shoulder C⁵. In order to accommodate the upward movement of the sheet as the actuator bar advances, the arm 60 C³ is pivotally supported in a manner which

will be further explained. In case the sheet is not properly positioned against the front gages, then as the bar E advances it engages the shoulder C⁵ and carries the arm C³ forward with it, thus rocking the sleeve C' and 70 operating the throw-out mechanism.

In order that the shoulder C⁵ at the end of the recess C⁴ may be brought into proper relation to the line of the front gages, it is desirable that the arm C³ be so mounted that it 75 may be adjusted longitudinally. Since the longitudinal adjustment of the arm would vary the height of the arm and thus tend to move the shoulder C⁵ out of line with the actuator bar, it is also desirable that the arm 80 be adjustable about its pivot as well as longitudinally. In order that these adjustments may be conveniently and simultaneously effected in such manner that the shoulder C⁵ will be adjusted in line with the movement of 85 the reciprocating bar E, I prefer to support the arm C³ in the manner shown in Fig. 2. As shown in this figure and in Fig. 1, the arm C³ is pivoted at its rear end to one end of a lever C⁶ which is in turn pivoted to an arm C⁵ 90 secured to the sleeve C'. The opposite end of the lever C⁶ is held by means of a spring C⁹ in engagement with an adjusting screw C⁷ mounted in the arm C⁵. By turning the screw C⁷ the lever C⁶ may be swung about its pivot to move the arm C³ longitudinally and thus carry its free end forward or back in the line of travel of the sheet.

In order that the end of the arm may be maintained at the proper height as it is adjusted with relation to the line of the front gages, the arm is supported by means of an adjusting screw C⁸ upon an inclined support C⁹. The support C⁹ is properly shaped with relation to the path of movement of the pivoted end of the arm C³ to maintain the free end of the arm in proper relation to the reciprocating actuator bar as the lever C⁶ is adjusted to vary the position of the arm. In order that the arm C³ may turn about its 105 pivot and accommodate the rocking movement of the sleeve C' when the arm is advanced by the engagement of the actuator bar with the shoulder C⁵, the support C⁹ is 110 yieldingly mounted upon the arm C⁵. As 115 shown, this support is formed at the lower end of a lever C¹⁰ the upper end of which carries an adjusting screw C¹¹ arranged to bear against a leaf spring C¹² secured to the arm C⁵.

In applying the controlling mechanism to 120 a printing press I provide two or more arms C³ and co-operating actuator bars E, either of which will act to operate the throw-out mechanism in case the front edge of the sheet is 125 not brought into proper position between the arms and bars. I prefer to employ two sets of such controlling devices and to arrange them adjacent to the front gages. In order that the arms C³ may be adjusted transversely to correspond to the position of the front 130

gages, the supports C^5 are adjustably secured upon the sleeve C' by means of clamping screws C^{13} . In order that the actuator bars E may be conveniently adjusted transversely of the machine to correspond to the adjustment of the arms C^3 , these bars are adjustably connected with a transverse bar E' . This bar E' is provided at opposite ends with guiding slots E^2 embracing fixed pins E^3 and the bar is reciprocated to advance and retract the actuator bars through links E^4 connecting the ends of the bar E' with arms E^5 which are secured to the rock shaft D . The rock shaft D may be operated at proper intervals through a link E^6 pivoted at one end to an arm E^7 secured to the rock shaft and connected at the other end with any suitable operating means.

In Fig. 5 I have shown a modified construction in which the arm C^3 is secured to a lever C^{14} . In this construction provision is made for the longitudinal adjustment of the arm C^3 by securing the arm to the lever C^{14} by means of a screw C^{15} passing through a slot in the upper end of the arm. The arm is yieldingly supported by means of a spring C^{16} interposed between the rear end of the lever C^{14} and a nut C^{17} . The nut C^{17} is mounted on a screw-threaded rod C^{18} which is secured to the arm C^5 and projects downward through the rear end of the lever C^{14} . By turning the nut C^{17} the arm C^3 may be adjusted about its pivot to maintain the shoulder C^6 in line with the actuator bar E . The interposed spring C^{16} forms a yielding support which enables the arm C^3 to swing about its pivot as the arm is moved forward by the actuator bar in giving the arm C^3 and sleeve C' a rocking movement.

In Fig. 6 I have shown a modified construction for effecting the connection between the actuator bar and the arm through which the throw-out mechanism is operated. In this construction the recesses c^4 extend through the end of the arm c^3 and the actuator bar is provided with fingers e' adapted to pass through the recesses c^4 .

When the shoulders e^2 engage the arm c^3 this engagement in connection with the engagement of the shoulders c^5 with the under surface of the fingers e' lock the actuator bar and arm c^3 together so that the arm is carried forward with the actuator bar.

While I prefer to use a construction and arrangement substantially like that shown in Fig. 2, it will be understood that the details of construction and arrangement may be variously modified and changed without departing from the invention.

Without attempting to explain in detail the various constructions in which the invention may be embodied, what I claim and desire to secure by Letters Patent is:—

1. Controlling mechanism for machines acting on sheets, having in combination

front gages against which the sheet is registered, throw-out mechanism, an arm connected therewith arranged at one side of the path of the sheet and provided with a shoulder back of the line of front gages, an actuator arranged on the opposite side of the path of the sheets and rendered inactive by an interposed sheet. 70

2. Controlling mechanism for machines acting on sheets, having in combination front gages against which the sheet is registered, throw-out mechanism, an arm connected therewith arranged at one side of the path of the sheets, a recess in said arm back of the line of the front gages, and an actuator 80 adapted to engage said recess in the absence of a sheet between the arm and actuator. 75

3. Controlling mechanism for machines acting on sheets, having in combination throw-out mechanism, an arm connected therewith and arranged above the path of the sheets, a recess in said arm, and an actuator arranged below the path of the sheets and adapted to engage said recess in the absence of a sheet between the arm and actuator. 85 90

4. Controlling mechanism for machines acting on sheets, having in combination throw-out mechanism, an arm connected therewith and arranged above the path of the sheet, a shoulder on said arm located above the edge of the sheet when in position, and an actuator arranged below the path of the sheet and adapted to engage said shoulder in the absence of a sheet between the arm and actuator. 95 100

5. Controlling mechanism for machines acting on sheets, having in combination throw-out mechanism, an arm connected therewith, and a reciprocating actuator between which and the arm the sheets pass, a shoulder on said arm in line with the movement of the actuator, and means for adjusting said arm to vary the position of the shoulder in said line. 105

6. Controlling mechanism for machines acting on sheets, having in combination throw-out mechanism, an arm connected therewith and having its free end above the path of the sheets, a recess in the free end of the arm, and a reciprocating actuator bar arranged below the path of the sheets. 110 115

7. Controlling mechanism for machines acting on sheets, having in combination throw-out mechanism, an arm yieldingly connected therewith and having its free end arranged above the path of the sheets, a recess in the free end of the arm, and a reciprocating actuator bar arranged below the path of the sheets. 120

8. Controlling mechanism for machines acting on sheets having in combination throw-out mechanism, an inclined arm pivotally connected therewith and having its free end arranged above the path of the sheets, a reciprocating actuator below the 130

path of the sheets, a shoulder on the arm in line with the movement of the actuator, and means for adjusting said arm longitudinally and vertically.

- 5 9. Controlling mechanism for machines acting on sheets, having in combination front gages against which the sheet is registered, an arm having its free end arranged above the path of the sheets, a shoulder on 25 said arm back of the line of the front gages, a reciprocating bar arranged below the path of the sheets and prevented from engaging said shoulder by the sheet, and throw-out mechanism connected with said arm.
- 10 10. Controlling mechanism for machines

acting on sheets having in combination, front gages against which the sheet is registered, throw-out mechanism, a connected arm inclined toward the front gages and having its free end above the path of the sheets, a shoulder on said arm, a reciprocating actuator bar below the path of the sheets and prevented from engaging said shoulder by the sheet.

In testimony whereof I have affixed my 25 signature, in presence of two witnesses.

FRANK L. CROSS.
